SAW FEEDING APPARATUS

Ananias A. Kvalheim, Petaluma, Calif.

Application September 16, 1940, Serial No. 357,044

4 Claims. (CL 143—47)

This invention relates to saw feeding apparatus and is designed primarily as a means whereby a circular saw can be moved forwardly or backwardly as desired and relative to the work by means of a simple but efficient mechanism under constant control of the operator, and without interfering with the rotation of the saw.

A further object is to provide a means by which the shaft of the saw can be utilized as a feeding element for shifting the saw into or out of position.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the drawing, which is a plan view of the apparatus, the preferred form of the invention has been shown.

Referring to the drawing by characters of reference, 1 designates a suitable supporting frame provided with guide rails 2. A carriage 3 is mounted for movement within the frame and has transverse axles 4 on which are mounted wheels 5 adapted to travel along the rails so that the carriage will be properly guided.

Bearings 6 are mounted on the carriage and journalled therein is a shaft 7 of a circular saw 8. This shaft has one or more pulleys 9 whereby motion may be transmitted thereto through one or more belts 10 from the pulleys 11 of a motor 12, the motor being connected to and movable with the carriage and, in the structure illustrated, being suspended therefrom.

A cross-head 13 is pivotally mounted between its ends on frame 1 as indicated at 14 and, in the structure illustrated, has an arm or handle 15 extending therefrom. To the respective ends of this cross-head are attached cables 16 and 17 the opposite ends of which are fastened securely to the frame as shown at 18. Cable 16 is wrapped in one direction about the shaft 7 while cable 17 is wrapped in the opposite direction.

Under normal conditions the cables are slack so that the shaft 7 can revolve freely within the convolutions 19 and 20 forming parts of the respective cables.

Assuming that the shaft 7 is rotating in the direction indicated by the arrow, it will be obvious that when the cross-head 13 is shifted to the position indicated by broken lines in the drawing,

the cable 16 will be drawn taut while additional slack will be supplied to the cable 17. As a result of this action the convolutions 19 will be tightened on the shaft 7 and said shaft will therefore be caused to wind cable 16 therearound so that the carriage will be moved toward the fixed end 18 of the cable. By shifting the cross-head to its other extreme position, however, the convolutions 19 will be loosened and cable 16 rendered slack while cable 17 will be drawn taut and its convolutions 20 will be tightened. As a result, continued rotation of the shaft 7 in the direction indicated by the arrow will result in the carriage 3 being moved toward the cross-head due to the fact that cable 17 will be wound on the shaft 7. Thus by manipulating handle 15 and cross-head 13, the movement of the carriage 3 in either direction can be controlled readily. Obviously as the carriage is moved, the saw and the motor will also be moved therewith.

What is claimed is :

1. The combination with a movable carriage, and a frame for supporting and guiding the same, of a shaft journalled on the carriage, a circular saw carried by the shaft, cables anchored at one end to the frame and wrapped in opposite directions respectively about the shaft, and means on the frame and connected to the cables for placing either of said cables under tension.

2. The combination with a movable carriage, and a frame for supporting and guiding the same, of a shaft journalled on the carriage, a circular saw carried by the shaft, cables anchored at one end to the frame and wrapped in opposite directions respectively about the shaft, and means on the frame and connected to the cables for placing either of said cables under tension, said means including a pivoted cross-head connected at its ends to the respective cables, and manually-operated means for shifting the cross-head.

3. The combination with a frame and a carriage mounted for sliding movement relative thereto, of a shaft journalled on the carriage, a circular saw rotatable with and carried by the shaft, separate cables anchored at one end and wrapped in opposite directions respectively about the shaft, a cross-head pivoted between its ends, the ends of the cross-head being secured to the other ends of the respective cables, and means for swinging the cross-head on its pivot for tightening either of the cables about the shaft.

4. The combination with a structure having guides, and a carriage mounted for back and forth sliding movement relative to the frame and

guides, of a shaft journaled on the carriage, a circular saw carried thereby, means on the carriage for rotating the shaft in one direction, separate cables anchored at one end and wrapped in opposite directions respectively about the shaft, a cross-head pivotally mounted between its ends on the structure and connected at its ends

5 to the other ends of the respective cables, and means for shifting the cross-head to tighten either of the wrapped portions of the cables thereby to move the carriage in either direction relative to the structure.

ANANIAS A. KVALHEIM.
